UNITED STATES PATENT OFFICE.

IRA T. WOLFE, OF SEATTLE, WASHINGTON.

AUTOMATIC VENDING-MACHINE.

1,267,730.

Specification of Letters Patent. Patented May 28, 1918.

Application filed May 10, 1915. Serial No. 27,122.

To all whom it may concern:

Be it known that I, IRA T. WOLFE, a citizen of the United States, residing at Seattle, in the county of King and State of Washington, 5 ton, have invented certain new and useful Improvements in Automatic Vending-Machines, of which the following is a specification.

This invention relates to improvements in 10 automatic vending machines, and particularly to automatically operated devices for opening and filling paper bags, and the object of this improvement is to provide an accurate and reliable machine that will open 15 a paper bag and fill it with a commodity to be sold in response to the insertion of a coin into such machine.

The invention consists in the novel construction, adaptation and combination of 20 parts, as will be more fully described in the following specification, illustrated in the accompanying drawings and finally pointed out in the appended claims.

In the accompanying drawings, Figure 1 25 is a view partly in side elevation and partly in vertical section of a machine embodying the invention; Fig. 2 is an enlarged view in side elevation of the bag-opening and filling mechanism, certain parts being shown in section; Fig. 3 is a view in horizontal cross-section on broken line 3—3 of Fig. 2; Fig. 4 is an enlarged view in cross section on broken line 4—4 of Fig. 1; Fig. 5 is view in cross-section of certain details of the invention 35 illustrating an electric circuit that is connected therewith; Fig. 6 is a fragmentary view in perspective of a conveyer, and Fig. 7 is a fragmentary sectional view illustrating a portion of the coin mechanism.

Referring to the accompanying drawings, 40 throughout which like reference numerals indicate like parts, the numeral 1 indicates the casing of a vending machine embodying this invention, and 2 indicates a hopper that 45 is disposed therein and adapted to contain pop-corn or other commodity that is offered for sale.

The hopper 2 is provided with an endless 50 conveyer 3 having buckets 4 of a form more clearly shown in Fig. 6, that are driven continuously by a motor 5 in the direction indicated by the arrow A, to elevate material from the hopper 2 into a measuring chute 6 that is connected by a passageway 7 with the 55 top portion of such hopper, as shown in Fig. 1.

The buckets are filled as they pass upwardly through the lower portion of the hopper 2 and move with their open sides against the side of such hopper until they 60 are opposite to the passageway 7, at which point the contents of each bucket are delivered to the chute 6.

When the chute has become filled, the buckets will carry past such chute and will 65 dump their contents back into the hopper 2, thus giving the appearance of a continuous supply of fresh material being delivered to such hopper.

Within the lower front portion of the cas- 70 ing 2 is a segmental shaped sack holder 8 that is supported on standards 9 and is adapted to receive folded sacks 10 that are to be opened and filled. The sack-holder 8 forms a support for a transverse shaft 11 75 that is slidably mounted therein and provided with a sleeve 12 having an outwardly projecting arm 13 that engages behind the sacks 10 to move them forward. The shaft 11 is provided with a worm-wheel 14 that 80 meshes with a worm 15 on a shaft 16 and the sleeve 12 is connected with the shaft 11 by a longitudinal slot 17 and a pin 18 that permits the shaft 11 to be moved longitudinally to throw the worm wheel 14 out of mesh with 85 the worm 15 when a fresh supply of sacks is placed in the sack-holder 8, as illustrated by broken lines in Fig. 3.

The paper sacks 10 are constructed in the usual manner so that when they are folded, 90 one edge 20 will project slightly above the other edge 20' to facilitate opening and such sacks are placed in the sack holder 8 with the upwardly projecting edge to the rear, whereby it may be engaged by a tongue 21 95 on the front end of the holder 8 to slightly open the top of the foremost sack in such holder. Spring clips 22 are provided on the front end of the sack holder 8 to exert a yielding pressure against the sacks 10 and 100 such clips are adapted to be sprung outwardly to release the sacks one at a time, as hereinafter explained.

The sacks 10, after they are opened slightly at the top by the tongue 21, are in a 105 position to be entered and opened completely by a vertically movable expansible sack-opener consisting in two members 23 and 24 that are pivotally secured to one end of a cross-arm 25 that is articulated with the 110 frame of the machine. The cross-arm 25 is supported in a raised position by an upright

post 26 that rests on a cross-pin 27 extending between two spaced disks 28 and 28¹ that are mounted on a shaft 30 and are adapted to be rotated by a motor 31 connected with the shaft 30 by worm-wheel 32 and worm 33.

5 A ratchet-wheel 34 is provided on the shaft 30 and insulated from the disk 28, and a spring-pressed pawl 35 is secured to the disk 28 and is adapted, when released, to 10 engage with the ratchet wheel 34 to lock the disk 28 and wheel 34 together and to close an electrical circuit formed by circuit wires 36 and 37 that have contact brushes 38 and 40 engaging with the disk 28 and ratchet-wheel 34, respectively, and connect the motor 31 with a battery 41 or other source of electric current, as more clearly illustrated in Fig. 5, whereby such motor may be energized.

15 When the machine is at rest, the pawl 35 is supported above the ratchet wheel 34 by a stud 42 on an arm 43 that is fulcrumed on the shaft 30 and the arm 43 is provided on one end with a flat plate 44 upon which 20 a coin C may be dropped through a slot 45 to tilt the arm 43 into an inclined position, and release the pawl 35.

If desired, the shaft 30 may be driven continuously and the electrical connections with 25 the ratchet wheel 34 and disk 28 may be left out, the pawl 35 then serving only to lock the ratchet wheel 34 and disks 28 and 28¹ together when it is released.

When the disks 28 and 28¹ begin to move, 30 the support 26 will encounter a stop 46 and the pin 27 will move out from under such support and permit the arm 25 together with the bag-opening members 23 and 24 to drop downwardly into a sack 10; the pin 27 will then engage with suitable extensions 47 on the member 23 and will spread the members 23 and 24 apart, as shown in Fig. 2, and open the sack in readiness to be filled.

35 The end of the chute 6 is provided with a hinged shutter 48, having a spring 50 to retain it in a closed position and an outwardly extending arm 51 that is adapted to be engaged by a pin 52 in the member 23 to 40 open such shutter when the sack-opening device is lowered, the shutter 48 being suitably shaped to form a chute that is adapted to project slightly within an opening 49 in the member 24 to deliver the contents of the 45 chute 6 between the members 23 and 24 and into a sack 10 when the members 23 and 24 are moved apart.

After the sack has been filled, the sack-openers 23 and 24 will be engaged by pins 53 on the peripheries of the disks 28 and 28¹ to move the lower end of such openers outwardly into a position as illustrated by broken lines in Fig. 2, and permit the sack 10 to drop downwardly through an opening 54 into a position where it is accessible to

the purchaser, and the pin 27, after the disks 28, 28¹ have made substantially one-half of one revolution, will engage with the bottom end of the support 26 in the position shown by dotted lines in Fig. 2 and will lift 70 the arm 25 and sack-openers 23 and 24 into the position shown in Fig. 1. As the disks 28, 28¹ complete their revolution, the pawl 35 will engage with the stud 42 and be lifted from the ratchet wheel 34, thus stopping the 75 mechanism until such pawl is again released by the insertion of a coin.

When the bag-openers 23, 24 are moved outwardly by the pins 53 to release the filled sack, the pin 52 will release the arm 51 and permit the shutter 48 to close the end of the chute 6. The downward movement of the sack-openers 23, 24 is limited by a stirrup 55 that engages with and forms a guide for the free end of the arm 25.

80 The shaft 16 is provided with a ratchet-wheel 56 engaged by a pawl 57 and adapted to be rotated intermittently by a spring-pressed plunger 58 that passes through suitable guides 60 and is connected with a tubular member 61 within which a rod 62, that is connected with the arm 25, is slidably disposed, the rod 62 being adapted to strike on the bottom of the tubular member 61 each time the sack-openers 23, 24 are lowered to 85 move the ratchet wheel 56 a short distance, thus actuating the worm 15 and worm-wheel 14 to rotate the shaft 11 slightly and move the sacks 10 forward a slight distance.

85 The chute 6 is articulated with the hopper 2 by a hinge 63 and is connected by a link 64 with an angular bar 65 that is pivotally secured to the sack-holder 8, and a weight arm 66 carrying a movable weight 67 is secured to the upper end of the chute to lift 100 the lower end of such chute and move the angular bar 65 in one direction, and close the coin slot 45 when no weight is contained in the chute 6. When the chute 6 is filled with material, the weight of such material will overbalance the weight 67 and lower the outer end of such chute, thus moving the angular bar 65 in an opposite direction and opening the coin chute. This arrangement prevents the public from inserting money into the machine when there 105 is no material in the chute 6 to fill the sacks 10.

110 The bag-opener 23 is connected with the arm 25 by a spring 70 whereby the lower 120 ends of the members 23 and 24 are held in contact with the lip 21 as they move downwardly to insure that they will enter a sack 10 and the support 26 is connected with the member 24 by a spring 71 to hold such support in engagement with the pin 27.

115 The opener 24 is provided with a spring supported notched bar 72 that projects outwardly through a slot 73 in the opener 23 and engages with such opener 23 as shown 130

in Fig. 2 to hold the openers 23 and 24 apart after the sack has been opened, the bar 72 being adapted to engage with a stop 74 to cause it to release the member 23 and permit the members 23 and 24 to close when they are raised.

The operation of this sack opening and filling device is as follows: The commodity to be sold is placed in the hopper 2 and is elevated into the chute 6 by the buckets 4. When the chute is filled, the buckets will dump back into the hopper, thus keeping up a continuous movement of the commodity and tending to attract the attention of the public.

When a coin is inserted through the slot 45 the pawl 35 will be released and the disks 28, 28¹ rotated to drop the sack-openers and open a sack 10. When the sack-openers are lowered, the pin 52 will engage with the arm 51 and open the chute 6 to direct the contents of such chute downwardly between the openers 23 and 24 into a sack 10.

After the sack has been filled, the lugs 53 will engage the openers 23 and 24 and move the bottom ends of such openers outwardly, thus permitting the filled sack to drop downwardly through the opening 54 where it may be removed by the purchaser.

As soon as the pin 27 reaches the lowermost point in its travel, it will engage with the bottom end of the support 26 and lift the sack-opening devices into position for another operation, the stud 42 engaging and lifting the pawl 35 to stop the rotation of the disks 28, 28¹ when the opening members 23 and 24 have been lifted.

The bag-holder 8 is of arcuate shape with the shaft 11 as a center and the sacks 10 being of greater thickness at the bottom than the top lie on radial lines within such bag-holder.

What I claim as my invention, is—

1. In an automatic vending machine, a receptacle for paper bags, said bags each having the rear edge of its opening projecting above its forward edge, means to impart pressure upon said paper bags to impel them in forward directions, and a tongue rigidly connected to said receptacle and adapted to be engaged by said rear edge of the foremost of said bags to cause such bags to gape open.

2. In an automatic vending machine, a receptacle for paper bags, said bags each having the rear edge of its opening projecting above its forward edge, means to impart pressure upon said paper bags to impel them in forward directions, a tongue adapted to engage said rear edge of the foremost of said bags to cause such bags to gape open, and resilient devices provided in the forward end of said receptacle to exert a yielding pressure against the lower portion of said bags.

3. In an automatic vending machine, a receptacle for paper bags, said bags each having the rear edge of its opening projecting above its forward edge, means to impart pressure upon said paper bags to impel them in forward directions, a tongue adapted to engage said rear edge of the foremost of said bags to cause such bags to gape open, separable bag-opening members arranged to enter said opened end of the bag, and means to separate said members to expand said bag.

4. In an automatic vending machine, a receptacle for paper bags, said bags each having the rear edge of its opening projecting above its forward edge, means to impart pressure upon said paper bags to impel them in forward directions, a tongue adapted to engage said rear edge of the foremost of said bags to cause such bags to gape open, resilient devices provided in the forward end of said receptacle to exert a yielding pressure against the lower portion of said bags, separable bag-opening members arranged to enter said opened end of the bag, and means to separate said members to expand said bag.

5. In an automatic vending machine, in combination with devices for holding a paper bag in aligned position, separable bag-opening members comprising two substantially flat plates pivoted together at their upper end, and adapted to be projected within said bag, means to separate said members to expand the bag, said members affording, when separated, a guide-way for material to fill said bags.

6. In an automatic vending machine, in combination, a chute wherein material to be vended is retained, and a bag-opening device consisting of two substantially flat plates pivoted together at their upper end, and adapted to be separated to expand a paper bag container, the opening between said members when separated affording a passageway for said material from said chute to the container.

7. In an automatic vending machine, a hopper for storing pop-corn or the like, and a chute adapted to contain a predetermined quantity of said pop-corn, said chute having an open end communicating with said hopper, carriers operatively mounted to convey pop-corn from said hopper to said chute and having an open end co-operating with the walls of said hopper to retain the pop-corn therein until registered with said open end of the chute.

8. In an automatic vending machine, the combination with a receptacle for paper bags, of means for opening the top of the foremost of said bags and bag opening members comprising two substantially flat plates adapted to enter a bag and then be separated to extend the bag, the said plates when

- separated constituting a chute for the passage of material into the bag.
9. In an automatic vending machine, the combination with a receptacle for paper bags, of means for feeding said bags forwardly in said receptacles, apparatus for slightly opening the top of the foremost of said paper bags, and bag opening members comprising two flat plates having a thin, 5 tapering end adapted to be projected into a bag in close proximity to the bottom thereof and then be separated to open the bag, the said plates when separated constituting a chute for the passage of material into the bag.
10. In an automatic vending machine, in combination with devices for holding paper bags in aligned position, and a tongue adapted to engage the rear edge of a bag aperture to cause the bag to gape open, of a bag-filling device arranged for movement to enter said partly opened bags to distend the same, and guided into said bag by contact with said tongue.
11. An automatic vending machine comprising a receptacle for paper bags, means for feeding said bags forwardly in said receptacle, a tongue for spreading the top of the foremost one of said bags, opening devices guided by said tongue arranged to enter said foremost bag and open it, said opening devices affording communicative connections between a source of supply of vendible material and said bag.
12. An automatic vending machine, comprising a receptacle for paper bags, means for feeding said bags forwardly in said receptacle, a tongue for slightly spreading the top of the foremost one of said bags, bag-opening devices adapted to enter said foremost bag, means for expanding said bag-opening devices, a chute adapted to deliver material into said opened bag a hopper, and means for conveying material from said hopper into said chute.
13. An automatic vending machine, comprising a receptacle for paper bags, means for moving said bags forwardly in said receptacle, spring clips to releasably hold said bags in said receptacle, means for slightly spreading the top of the foremost bag in said receptacle, a separable bag-opener adapted to enter and open said foremost bag, means for filling said bag after it is opened, and means for withdrawing said bag-opener.
14. An automatic vending machine, comprising a receptacle for paper bags, means for feeding said bags forwardly in said receptacle, a tongue adapted to spread the tops of said bags slightly, a bag-opener adapted to enter said bags, said bag-opener consisting in two flat members that are hinged at their upper ends, and means for spreading the bottom ends of said bag-opening members apart to open said bag.
15. An automatic vending machine, comprising a receptacle for paper bags, means for feeding said bags forwardly in said receptacle, a tongue to spread the top of the foremost bag in said receptacle slightly, a bag-opener consisting in two flat plates that are hinged at their top ends and adapted to be moved apart to open a bag, means for supporting said bag-opener in a raised position, means for lowering said bag-opener, and means for expanding and raising said bag-opener.
16. An automatic vending machine, comprising a receptacle for paper bags, said receptacle being of segmental form, whereby, when a plurality of paper bags are placed therein, each of said bags will lie in a radial plane of said receptacle, means for delivering said bags one at a time from said receptacle, means for opening said bags, and means for filling said bags.
17. An automatic vending machine, comprising a receptacle for paper bags, means for advancing said bags in said receptacle, and resilient devices provided in the forward end of said receptacle to exert a yielding pressure against the foremost one of said bags.
18. An automatic vending machine, comprising a receptacle for a commodity to be sold, a chute for holding a predetermined amount of said commodity, a receptacle for paper bags, an arm for feeding said bags forwardly in said receptacle, a two-part bag-opening member, means for lowering said bag-opening member into the foremost one of said bags, means for spreading the two parts of said bag-opening member to open said bag and form a passageway thereinto, means for moving the bottom end of said bag-opening member outwardly to release a filled bag, and means for raising said bag-opening member.
19. An automatic vending machine, comprising a receptacle for paper bags, a two-part bag-opener, one part of said bag-opener having an opening therethrough, a chute, an extension pivotally secured to the end of said chute and normally adapted to close said chute, and means for lowering said extension when said bag-opener is lowered to cause said extension to project within said opening in said bag-opener to deliver the contents of said chute thereinto.
20. An automatic vending machine comprising a frame, a horizontal arm pivoted at one end to said frame, a bag-opener comprising two members that are pivoted to said arm at their upper ends, rotatably mounted spaced disks, a bar extending between said disks, a leg pivoted to said arm and having a notched end adapted to rest upon said bar, a stop engaging said leg whereby, when said disks are rotated, said leg will drop off of said bar and lower said

bag-opening device and will then be reengaged by said bar and lifted to its original position as said disks continue to rotate, and means for arresting the movement of said disks at the end of one complete revolution.

21. A device of the class described, comprising a frame, a horizontal arm pivoted at one end to said frame, sack-opening members pivotally secured to the other end of said arm, a leg pivotally secured to said arm, rotatably mounted spaced disks, means for effecting a complete rotation of said disks, a cross-bar connecting said disks and upon which said leg is adapted to rest, and means engaging said leg to cause said leg to drop off of said cross-bar when said disks begin to rotate.

22. A structure of the class described, comprising a receptacle for paper bags, a shaft extending cross-wise of said receptacle, an arm secured to said shaft, a bag-opening device, means for raising and lowering said bag-opening device, and means connected with said shaft for advancing said arm a predetermined amount upon each downward movement of said bag-opening device.

23. In an automatic vending machine, a holder for paper bags, consisting in a segmental shaped receptacle and a follower adapted to press said bags forwardly, said follower being pivotally mounted in the axis of said holder.

24. In an automatic vending machine, a holder for paper bags consisting in a segmental shaped receptacle, a follower arranged to press upon the rear side of said bags, consisting of an arm pivoted in the axis of said holder, and driving mechanism for actuating said arm to move said bags in forward directions.

25. In an automatic vending machine, a

holder for paper bags consisting in a segmental shaped receptacle, a follower arranged to contact upon the reverse side of 45 said bags, consisting in an arm pivotally mounted in the axis of said holder, and driving mechanism for actuating said arm to move said bags in forward directions.

26. In an automatic vending machine, a 50 holder for paper bags, a follower arranged to contact upon the reverse side of said bags, and actuating mechanism adapted to advance said follower forwardly at a uniform rate of travel and with uniform pressure 55 upon said bags when said vending machine is operated, and means to cause the foremost of said bags to gape open.

27. In an automatic vending machine, bag 60 opening mechanism consisting in two substantially flat plates pivotally connected at one of their ends and adapted to be protruded into a paper bag, and means to separate said members to expand said bag.

28. In an automatic vending machine, the combination of a chute for holding a desired amount of a vendible commodity, bag-opening mechanism consisting in two separable members pivotally connected at their 70 upper ends and adapted to be lowered and protruded into a bag, and affording a passageway for said commodity into said bag, means to separate said members to expand said bag, and means whereby the contents of said chute is delivered into said passageway simultaneously with the lowering of said members.

Signed at Seattle, Washington, this 23rd day of April, 1915.

IRA T. WOLFE.
